(57) **CLAIM**

I claim the ornamental design for an electrical rocker switch actuator, as shown and described.

DESCRIPTION

FIG. 1 is a top plan view of an electrical rocker switch actuator showing my new design.

FIG. 2 is a left side elevational view thereof, the right side being a mirror image thereof; and,

FIG. 3 is an in elevational end view thereof.

The broken/phantom lines show the environment for the claimed design and are offered for illustrative purposes only, and form no part of the claimed design.
